UNITED STATES PATENT OFFICE.

JOHN F. MEYER, OF CHICAGO, ILLINOIS, ASSIGNOR, BY MESNE ASSIGNMENTS, TO ECLIPSE SPECIALTY MANUFACTURING COMPANY, A CORPORATION OF ILLINOIS.

TIMER FOR INTERNAL-COMBUSTION ENGINES.

1,392,694.

Specification of Letters Patent.

Patented Oct. 4, 1921.

Application filed September 10, 1917. Serial No. 190,477.

To all whom it may concern:

Be it known that I, JOHN F. MEYER, a citizen of the United States, residing at Chicago, in the county of Cook and State of Illinois, have invented certain new and useful Improvements in Timers for Internal-Combustion Engines, of which the following is a specification.

My invention relates to improvements in electrical connections, and has particular reference to connections between engines and commutators in self propelling vehicles. The object of the present invention is to provide a simplified, easily adjusted and economically constructed timer with reference to the protection of the conducting wires, their arrangement to obviate confusion, oiling facilities, avoiding short-circuiting, double sparking, back-firing causing breakages of crank-shafts, injuries to operators, etc. and to prearrange the wires in their proper firing order to protect the operators against the mistakes often made in selecting such wires in the usual manner.

With the above-named objects in view my invention consists in the novel construction, combination and arrangement of parts, all as hereinafter described in detail, illustrated in the accompanying drawing and more particularly pointed out in the appended claims.

In the drawing—

Figure 1 is a side elevation of engine parts with my invention applied thereto.

Fig. 2 is a perspective view of my invention with sections of the device separated.

Fig. 3 is a section taken substantially on line 3—3 of Fig. 1.

Fig. 4 is a section taken substantially on line 4—4 of Fig. 3.

In the several views 2 represents an engine part or cylinder and 3 is the engine casing provided with coverings for a gear wheel 4 on the driving-shaft —5— which meshes with a gear wheel 6 which is keyed to the cam-shaft —7— to which is secured a collar 8 that is provided with a lug 9 to which a curved lever 10 is pivoted and a lug 11 that is connected with the power end —12— of the lever by a coiled tension spring 13. An anti-friction contact roller 14 is pivoted in a forked load or resistance end 15 of said lever. By load or resistance end is meant that part of the lever where the power is applied. The roller 14 travels in the well

known manner on the inner periphery of a commutator ring 16 that is provided with a contact plate for each cylinder to be fired. In the present instance provision is made for the usual four cylinders represented by contact plates 17, 18, 19 and 20 which are secured to the ring in any suitable manner, as, for instance, by means of rivets 21 which pass through the ring and plates as shown. On the ring 16 is the usual connecting-rod 65 lug 22 with a hole 23 therein for a pivot 24 on which is mounted one end of a connecting rod 25 that is operated by a crank 26 on a shaft 27 that is rotated by a lever 28 working on a quadrant 29 and controlling the advancement or retardation of the ignition spark for each engine cylinder. 30 is the usual steering post within a stationary housing, hollow bearing or pipe 31 which may also serve as a bearing for the throttle-shaft 75 —32— provided with a handle or lever 34 working on a quadrant 35.

In the embodiment of my invention the cap over the commutator ring is represented by the numeral 36 and is provided with a 80 preferably integral curved arm 37 through which the wires are led protected to the ring 16. In the latter are combination dowel and contact pins which take the place of the usual exposed binding posts, and same are 85 indicated by the numerals 38, 39, 40 and 41. These extend from the ring parallel to its axis and are engaged with holes or dowel pin sockets 42, 43, 44, and 45 that are formed in the cap 36. These dowel pins extend 90 from the contact plates and serve both as electrical connections and as joints or connections between the cap and the ring. The respective contact plates are connected with wires 46, 47, 48, and 49 which connect the 95 spark plugs with the commutator. The timer is held in place for rotary adjustment by the usual form of bracket arm 50 that is secured by a screw or bolt as at 51 to a stationary part of the engine and is provided 100 with a lug 52 which engages a depression or indentation 53 in the cap. An oil tube 54 with a capped cup 55 leads from the free end of the arm 37 to the interior of the commutator ring. This permits oiling the moving parts in the latter without the usual necessity of stopping the machine. In the present embodiment the cap 36 and its arm 37 are made in two spaced apart sheets or 105 layers of fibrous and non-conducting mate- 110

rial —57 and 58— separated to provide room for the wires and oiling tube by a narrow strip 59 at the edges of and between the layers 57 and 58. From the arm 37 the wires 5 are conducted through a common form of flexible tube or cable cover 61. The latter is joined to the arm 37 by a coupling-piece or reducer-cap 60.

In the above-described construction the 10 wires are completely incased and protected against breakage by engine-moved parts, such as the fan, and are instantaneously removable as substantially a part of the cap for the commutator ring, or attachable with 15 equal facility and speed by reason of the cap-holding pins serving as electrical connections. These pins are removed from exposure to oil splash and water, or other foreign substances which are a frequent cause 20 of short-circuiting.

By reference to Fig. 1 it will be noticed that the insulating or wire-incasing arm 37 projects horizontally from the timing gear case—62— to carry the cable or wires to 25 one side instead of over the hot top of the engine where the wire insulations are often melted. In prevailing constructions the commutator ring and its pivotal cap are cast in one piece, and when the ring is worn un- 30 even, or otherwise damaged, its replacement includes the cap. In the present improvement the cap and its extension—the arm 37—are made a substantially permanent element, or one not involved in the renewal of the 35 wear portion, or ring 16. The ring separate, as shown most plainly in Fig. 2, makes it easier and less expensive to machine, or “finish” the rough casting. With the ends of the usual commutator rings closed by the 40 timing gear case and the cap the timing adjustment, or correctly arranging the firing points, is a matter of guesswork and repeated trials with the engine in motion. With the cap end or side of the ring open 45 after it has been placed in the timing gear case the position of the contact roller 14 with reference to the segments or contact plates 17, 18, 19 and 20, is so plainly exposed that the ring may be instantaneously adjusted to 50 place the roller on a segment or contact

plate, by properly lengthening or shortening the usual lever connections with the ring, when the corresponding engine cylinder's piston is on dead center.

The usual binding post connections between posts and segments 17 to 20 often become loose from the jarrings of the machine, thereby producing imperfect electrical conductivity. In the present improvement the dowel pins 38 to 41 and the segments are 55 one-piece stampings, and the spring arm 50 insures constant contact between the sockets or bushings that are engaged by the dowel pins. In replacing a worn ring 16 the wiring is not disturbed, this wiring being confined to the cap and its wire-covering extensions which are substantially integral with the cap. As the wires for the different cylinders are necessarily of different lengths, owing to the different distances of the different cylinders from the timer, the operator can make no mistake as to which wire is to be attached to each spark plug. Such mistake is apt to happen in connection with any substitute for a binding post, such as headed 65 wires or plain wires inserted in sockets electrically connected with the contact plates or segments.

Having thus described my invention, I claim as new and desire to secure by Letters 80 Patent—

1. In a timer, the combination with a gear case, of a commutator ring removably mounted on said case, a cap separably mounted on said ring and having a conduit 85 arm with wires therein, and coupling members upon said ring and cap which hold same together and connect them electrically.

2. In a timer, the combination of a commutator ring, a cap for said commutator ring, said cap being removable to expose the interior of said ring, a laterally extending arm on said cap adapted to serve as a wire-conduit, an oil cup on the end of said arm, and an oil-conducting tube leading from said 90 cup to the interior of said commutator ring.

In testimony whereof I have hereunto signed my name.

JOHN F. MEYER.
